US00D655154S

(12) **United States Design Patent**
Amos et al.

(10) **Patent No.:** US D655,154 S
(45) **Date of Patent:** ** Mar. 6, 2012

(54) **PACKAGE**

(75) Inventors: **Gregory Y. Amos**, Richmond, VA (US); **James D. Evans**, Chesterfield, VA (US); **Robert L. Kikkert**, Charles City, VA (US); **H. Cary Longest, Jr.**, Midlothian, VA (US); **Travis M. Garthaffner**, Midlothian, VA (US); **Christopher J. Hession**, Mechanicsville, VA (US)

(73) Assignee: **Philip Morris USA Inc.**, Richmond, VA (US)

(**) Term: **14 Years**

(21) Appl. No.: **29/353,152**

(22) Filed: **Jan. 4, 2010**

Related U.S. Application Data

(63) Continuation-in-part of application No. 29/311,483, filed on Mar. 30, 2009, now abandoned.

(51) **LOC (9) Cl.** **09-03**

(52) **U.S. Cl.** **D9/425; D9/407**

(58) **Field of Classification Search** D9/414, D9/415, 416, 418, 424, 425, 430, 432, 407; 206/528, 531; 220/9.1, 9.4, 890

See application file for complete search history.

Primary Examiner — Thomas Johannes

(74) *Attorney, Agent, or Firm* — Buchanan Ingersoll & Rooney PC

(57) **CLAIM**

The ornamental design for a package, as shown and described.

DESCRIPTION

FIG. 1 is a perspective view of a package according to a first embodiment of our new design, the other side being a mirror image thereof.

FIG. 2 is a rear elevational view thereof.

FIG. 3 is a front elevational view thereof.

FIG. 4 is a right side elevational view thereof, the other side being a mirror image thereof.

FIG. 5 is a top plan view thereof.

FIG. 6 is a bottom plan view thereof.

FIG. 7 is a perspective view of a package according to a second embodiment of our new design, the other side being a mirror image thereof.

FIG. 8 is a rear elevational view thereof.

FIG. 9 is a front elevational view thereof.

FIG. 10 is a right side elevational view thereof, the other side being a mirror image thereof; and,

FIG. 11 is a top plan view thereof, the bottom being a mirror image thereof.

1 Claim, 5 Drawing Sheets
